AUTOMATIC LOCKING AND RELEASING
DEVICE FOR SHIFT KEYS ON TYPE-
WRITERS

Robert Büchel, Gamprin, Liechtenstein

Application October 17, 1945, Serial No. 622,787
In Switzerland June 1, 1945

7 Claims. (Cl. 197—80)

1

The present invention relates to an automatic locking and releasing device for a typewriter shift key. In the devices of this type now used the shift key is locked in depressed position by a pawl which is released when a typewriter key is struck. Since the carriage of the typewriter, platen, and all the mechanisms connected therewith are relatively heavy and are thus carried by the shift key in above position, it then follows that in striking a key so much of the force so exerted is used up in releasing the pawl that the particular type bar operated no longer strikes the paper about the platen with sufficient force.

The object of the present invention is to reduce the power or force required for releasing the shift key by the type key to such an extent that in normal typing the power necessary for releasing the shift key is negligible.

The present invention resides in the fact that a locking member is drawn against a stop by a spring, and a return or resetting lever counteracts the former under the action of a spring and is held in cocked position by a catch releasable by a rod connected to a member universally operated by all character keys.

The foregoing parts are so arranged, that when the shift key is depressed, the locking member bears against the stop, thereby locking said shift key which may subsequently be released upon striking or depressing any character key.

The parts forming the locking and releasing mechanism may be arranged differently in different makes of typewriters.

In principle the locking member, the resetting lever and the catch holding the latter may be in fixed position on the machine, in which case the stop and the part which pushes back the resetting lever must be fitted on movable parts. If the said locking and resetting levers and the catch are mounted on a movable element as for instance the shift key, then the stop and the part which pushes the resetting lever back must be fixed.

In the accompanying drawings various embodiments of the invention are illustrated and in which—

Figure 1 shows on a reduced scale the shift key lever connected in the usual manner to the cylinder or platen carriage;

Figure 2 is a fragmental sectional view showing an embodiment comprising a locking member, resetting lever and catch in idle position all mounted on the shift key;

Figure 3 is a similar view to Figure 2 with the parts locked in shifted or upper case position;

2

Figure 4 shows an intermediate position of the locking device;

Figure 5 shows the locking device in position before returning to the initial Figure 2 position;

Figure 6 is a fragmental detail view showing the locking member, resetting lever and catch mounted on the up and down moving carriage;

Figures 7, 8, 9 and 10 are similar views to Figure 6 but showing the locking member, resetting lever and locking catch mounted on the stationary frame of the machine, while the stop and resetting lever actuating member are mounted on the shift lever;

Figure 11 shows a similar arrangement to Figure 9 with the exception that the resetting lever actuating member and stop are fixed on the carriage frame; and

Figure 12 is a fragmental sectional view showing one manner of connecting the locking tooth to the escapement mechanism.

Referring now to the drawings in detail, the shift key lever 1 shown in Figure 1 is swingably mounted in the usual manner on pivot 2 and connected at the rear thereof by means of a connection 3 to a frame 4 which carries the typewriter carriage in which is mounted the cylinder or platen 5. The frame, carriage and cylinder may be lifted or raised to upper case position by depressing the end 6 of the shift key 1. The said key 1 is guided at the front thereof in the slotted plate 7 usually provided at the front of the typewriter. Pivotaly mounted at 13 on the shift key 1 is a locking member 8 provided with a lever arm 9. The said arm 9 is connected by means of a spring 10 to a catch or locking tooth 11 pivotally carried by the shift key. The locking member when in normal idle position engages a roller 12 mounted on the machine frame. Also pivotally mounted on pivot 13 is a control or resetting lever 14 having an arm 23 to which is connected one end of a coiled spring 15, the opposite end of said spring being anchored on a pin 16 carried by the machine frame. The said lever 14 is provided with a second arm 24 which for co-operative engagement with the tooth 11, carries two lips 17 and 18, the lip 18 being arranged above and behind the lip 17 as viewed from the right side of Figures 2 to 5.

The space or distance between the lower lip 17 and upper lip 18 is somewhat larger than the tapered end 19 of the locking tooth 11 so that it may slide freely between said lips. When the shift-key lever 1 is depressed as shown in Figure 3 in order to lift the cylinder, locking member 8 is drawn under the roller 12 by the action

of the spring 10 thus keeping the shift key in depressed position.

In known manner, in striking key 108, a sub-lever 102 is moved which is rotatably supported in 109. The sub-lever actuates a type bar 100 which is supported in the segment 101. In segment shift mechanisms the segment is arranged movably and in other models immovably. The type bar in its movement toward the cylinder 110 pushes against the beam 111a of the shift bridge 111 which, by the member 103 and the guide 112 is displaceably supported in the segment 101 for movement towards the escapement mechanism 105. As is known, there have been provided in the escapement mechanism 105 the escapement dogs 106 and 107 by which the escapement wheel 104 is alternately stopped and released, which causes the latter to turn step by step. In typewriters with segment shift arrangements the shift bridge 111 with the member 103 moves downward or upward, and in machines without segment shift arrangements, the shift bridge 111 is moved horizontally only. As a rule, the type bar 100 acts on the beam 111a only after traveling $\frac{3}{4}$ of its movement. The shift bridge 111 is provided with a cross-piece 99 in which the pulling member or rod 20 is supported which is provided with a stop 20a. The pulling member or rod 20 is of such a design that it is moved by the shift bridge and releases the shift pawl or catch 11 as soon as the type bar 100 reaches a point 5-15 mm. in front of the cylinder 110.

The stop 20a is arranged in such a way that it is away from the cross-piece 99 by a distance of 20b when the shift key is in its position of rest, so that, when striking a key, the stop 20a of the pulling member 20 is not moved by the cross-piece 99. But as soon as the shift key is moved downwards, it pulls the pawl 11 so far down that the stop 20a lies against the cross-piece 99.

Now if a type bar is struck, the pulling member 20 is moved also, and the pawl 11 jumps into the position according to Figure 4, from which, when the type bar returns, it moves into position of Figure 5 and, in the position of rest of the shift lever, after putting the spring 15 under tension, again takes the position according to Figure 1.

In a similar manner, if necessary, the pulling members 20 of Figures 6 to 11 can also be actuated by way of intermediate members.

In the embodiment shown in Figure 6, a locking member 25 and resetting lever 26 are pivotally mounted on a pivot pin 27 carried by the carriage frame 28 which may be moved up and down. The carriage frame 28 is engaged by a roller 29 and lifted thereby when the shift-key lever 31 is depressed or swung about its pivot 30, the roller 29 being rotatably mounted on the shift-key lever extension 32 at the rear of the pivot 30. The locking member 25 is pressed against a roller 34 by means of a spring 33, so that the carriage frame when raised will remain in lifted position due to the engagement of the bottom of the locking member with the roller 34. When a character key is struck, locking catch 35 is pulled down by the tension rod 20 and releases the resetting lever 26 which is then free to be swung about the pivot 27 against a stop 37 on the locking member 25, by the action of a spring 36. The action of the resetting lever presses the locking member into cocked idle position against the spring 33 permitting the carriage 28 to again drop to lower position. In this downward movement, arm 38 of the resetting

lever 26 strikes against a pin 39 fixed to the frame of the machine and presses lever 26 into engagement with catch 35 and tensions spring 36 to hold the resetting lever ready for actuation by the operation of the next key.

The embodiment shown in Figure 7 comprises a locking member 41 and a resetting lever 42 pivotally mounted on a stud or pin 43 fixed on the machine frame 45 by means of a bracket 44 secured to said frame by a bolt 46. A spring 47 also secured to the frame 45 by the bolt 46 presses against a stop or ledge 48 on the locking member 41. An arm 49 of resetting lever 42 is movably connected to shift-key lever 51 by means of a slotted arm or link 50. A bolt or stud 53 on arm 49 fits slidingly in a slot 54 in arm 50 and is normally held against the bottom of said slot by a spring 52 secured at one end to the arm 49 and at its opposite end to the shift-key lever 51. Due to the above arrangement, the spring 52 becomes tensioned when the shift-key lever is depressed, the link 50 sliding down due to the slot and stud arrangement. The resetting lever 42 is normally held by a catch 55 pivotally mounted on a stud 56 fixed on the machine frame, the said catch being pressed upwardly by a spring 57. The locking roller 58 which abuts against the bottom of the locking member 41 when the shift-key lever is depressed, is pivotally mounted on the said shift-key lever 51.

Figure 8 shows the locked position of the shift-key lever 51. As in the other forms of the invention, the catch 55 is brought out of engagement with the resetting lever by a pull on the tension rod 20, permitting lever 42 to be swung against the stop 48 on the member 41 and swing same into a position to permit the roller 58 to come in advance of the said locking member upon the return of the shift-key lever to upper position, which action again swings the resetting lever by the link 50 into engagement with the catch 55.

The embodiment shown in Figure 9 is similar to that shown in Figures 7 and 8 with the exception that a roller 66 is fixed to the shift-key lever 65 and replaces the link 50, said roller normally abutting the underside of an arm 67 on a resetting lever 68.

The Figure 10 embodiment is similar to that shown in Figure 9, with the exception, however, that a roller 64 is arranged on a lever 72 connected with a shift-key lever 70 by means of a link 71, said arrangement replacing the roller 58 shown in Figures 7, 8 and 9 which is directly mounted on the shift-key lever 51. Likewise instead of the bracket 44 of the Figures 7, 8, and 9 embodiments, the Figure 10 embodiment provides a support 76 on the machine frame, which at its upper end has a pin or stud 75 upon which are pivotally mounted the locking member 73 and resetting lever 74. A catch 77 for engaging the resetting lever 74 is also pivotally supported on the support 76. A spring 78 is anchored at one end on the support 76 and at its opposite end on an arm 79 of the reset lever 74 and holds same against a roller 80 on the shift-key lever 70. Upon the depression of shift-key lever 70 roller 64 is brought below the locking member 73 and permits the spring 81 to pull said locking member into locking engagement with the said roller 64. During the depression of the shift-key lever, roller 80 moves away from the arm 79 of the resetting lever 74 and permits said resetting lever to contact pin 82 and reset the locking member 73 when catch 77 is released by tension rod 20.

Figure 11 shows a counterpart to the embodiment

ment illustrated in Figure 6. Locking member 83 is pressed against roller 87 by spring 84 fixed to bolt 85 on the frame. Roller 87 is fixed on frame part 88 which is lifted by roller 89 fixed on rear arm 90 of shift-key lever 91. Besides locking member 83, resetting lever 93 which is pressed against roller 95 by means of spring 94 fitted on frame 88, also pivots on bolt 92 fixed on the frame of the machine. Catch 96 is pressed against resetting lever 93 by spring 97 thus locking the former in cocked position. On lifting frame 88 by roller 89, locking member 83 comes under roller 87 thus preventing frame 88 from dropping. When catch 96 is released by tension rod 20, lever end 98 bears against stop 86 of locking member 83, so that the lock effected by roller 87 is released, thus enabling frame 88 to drop. When the frame moves downward, roller 95 rests against resetting lever 93 and brings it again into the position locked by catch 96.

What is claimed is:

1. In a typewriter having a frame structure, character keys, and a structure including a platen carriage and a shift-key mounted for movement from lower to upper case position with respect to said frame structure; a device for automatically locking said shift-key in upper case position and then releasing same, said device comprising a stop mounted on one of said structures, a pivotally mounted locking member mounted on the other of said structures and normally spring pressed against said stop, a spring actuated resetting lever pivotally and coaxially mounted with the locking member, a spring urged locking catch mounted on said other structure for operative engagement with the resetting lever, the said locking member being adapted to be brought into locking engagement with the stop when the shift-key is depressed to maintain said key in depressed position, a member universally actuated for movement by each typewriter character key when said keys are operated for typewriting, and means connecting said universally actuated member with the locking catch to move the catch and bring same out of locking engagement with the resetting lever at the completion of said typewriting operation to permit the resetting lever to swing the locking member out of locking engagement with the stop and permit the shift-key to return to normal position.

2. In a typewriter having a frame, a platen carriage, character keys and a shift-key connected to said carriage for moving same from lower to upper case position, a device for automatically locking said shift-key in upper case position and then releasing same, said device comprising a stop mounted on the typewriter frame, a locking member pivotally mounted on the shift-key, a resetting lever pivotally mounted on the shift-key coaxially with the locking member, a locking catch pivotally mounted on the shift-key in engagement with the resetting lever, a spring connected to the locking member and locking catch to normally hold said locking member against said stop, a spring exerting a tension against the resetting lever for maintaining same in locking engagement with the catch, the said locking member being adapted to be brought into locking engagement with the stop when the shift-key is depressed to maintain said key in depressed position, a member universally actuated for movement by each typewriter character key when said keys are operated for typewriting, and means connecting said universally actuated member with the locking catch to move the catch

5 and bring same out of locking engagement with the resetting lever at the completion of said typewriting operation to permit the resetting lever to swing the locking member out of locking engagement with the stop and permit the shift-key to return to normal position.

3. In a typewriter having a frame, a platen carriage, character keys and a shift-key connected to said carriage for moving same from lower to upper case position; a device for automatically locking said shift-key in upper case position and then releasing same, said device comprising a stop mounted on the type writer frame, a locking member pivotally mounted on the shift-key, a resetting lever pivotally mounted on the shift-key coaxially with the locking member, the said locking member being formed with a recess along its upper surface, a lip at the rear extremity of said recess, an upper and a lower lip on the resetting lever, the lower lip being in advance of the upper lip and extending into the locking recess, a locking catch pivotally mounted on the shift-key normally in engagement with the lower lip of the resetting lever, a spring connected to the locking member and locking catch to normally hold said locking member against said stop, a spring exerting a tension against the resetting lever for maintaining same in locking engagement with the catch, the said locking member being adapted to be brought into locking engagement with the stop when the shift-key is depressed to maintain said key in depressed position, a member universally actuated for movement by each typewriter character key when said keys are operated for typewriting, and means connecting said universally actuated member with the locking catch to move the catch and bring same out of locking engagement with the resetting lever lower lip and bring said catch into locking engagement with the upper lip during the downward stroke of any of said character keys, the said resetting lever being swung about its pivot by its spring during said movement of the catch to bring its lower lip into engagement with the locking member lip, the said connecting means disconnecting the catch from the upper lip upon the return stroke of the character key and bringing said catch between the upper lip and lower lip of the resetting lever to permit the lower lip of said resetting lever to swing the locking member out of locking engagement with the stop and permit the shift-key to return to normal position.

4. A device according to claim 1, wherein the locking member, resetting lever and catch are mounted on the typewriter frame, and the stop is mounted on the shift-key.

5. A device according to claim 1, wherein the locking member, resetting lever, and catch are pivotally supported on the platen carriage and the stop is supported on the typewriter frame.

6. In a typewriter having a frame, a platen carriage, character keys and a shift-key connected to said carriage for moving same from lower to upper case position; a device for automatically locking said shift-key in upper case position and then releasing same, said device comprising a stop mounted on the shift-key, a bracket secured to the frame of the typewriter, a locking member and a resetting lever coaxially and pivotally mounted on said bracket, a ledge on the locking member, the resetting lever comprising a pair of arms, a link pivotally connected to the shift-key at one end and provided with a slot at its opposite end, a pin on one of said re-

setting lever arms slideable in said slot and normally resting at the bottom thereof, a spring secured at one end to said arm and at its opposite end to the shift-key, a spring for normally pressing the locking member against the stop, a catch pivotally mounted on the typewriter frame at one end and in locking engagement with the other of said resetting lever arms, a spring for normally maintaining the catch in said locking engagement, the said locking member being urged by its spring over the stop when the shift-key is depressed to maintain the key in depressed position and the link sliding on the pin on the resetting lever arm to bring the top of the slot into engagement with the pin, a member universally actuated for movement by each typewriter character key when said keys are operated for typewriting, and means connecting said universally actuated member with the locking catch to move the catch and bring same out of locking engagement with the resetting lever arm at the end of said typewriting operation to permit the catch engaging arm of the resetting lever to contact the locking member ledge to swing the locking member out of locking engagement with the stop and permit the shift-key to return to normal position.

7. In a typewriter having a frame, a platen carriage, character keys and a shift-key connected to said carriage for moving same from lower to upper case position; a device for automatically locking said shift-key in upper case position and then releasing same, said device comprising a stop mounted on the typewriter frame, a locking member pivotally mounted on the typewriter carriage, a resetting lever pivot-

ally and coaxially mounted with said locking member, the resetting lever comprising a pair of arms, a pin on the typewriter frame against which one of said arms normally bears, a spring connected to said arm for normally holding same against said pin, a catch pivotally mounted on the carriage, a spring for holding said catch in locking engagement with said other resetting lever arm, a roller on the shift-key lever in engagement with the carriage for raising same when the shift-key is depressed, a spring for normally pressing the locking member against the stop and moving same thereabove for locking engagement therewith when the said shift-key is depressed to maintain said carriage in shifted position, a member universally actuated for movement by each typewriter character key when said keys are operated for typewriting, and means connecting said universally actuated member with the locking catch to move the catch and bring same out of locking engagement with the resetting lever at the completion of said typewriting operation to permit the resetting lever to swing the locking member out of locking engagement with the stop and permit the carriage to return to normal position.
